UNITED STATES PATENT OFFICE.

HENRY SEAMAN, OF MEMPHIS, MISSOURI.

WASHING-MACHINE.

SPECIFICATION forming part of Letters Patent No. 402,355, dated April 30, 1889.

Application filed November 12, 1888. Serial No. 290,597. (No model.)

To all whom it may concern:

Be it known that I, HENRY SEAMAN, a citizen of the United States, residing at Memphis, in the county of Scotland and State of Missouri, have invented certain new and useful Improvements in Steam Washing-Machines; and I do hereby declare that the following is a full, clear, and exact description of the same, reference being had to the annexed drawings, 10 making a part of this specification, and to the letters and figures of reference marked thereon.

This invention relates to certain new and useful improvements in steam washing-machines of that class in which a cylinder for receiving the clothes to be washed is rotated in a vessel or boiler containing heated water.

The invention is designed more particularly as an improvement upon the device shown 20 in Patent No. 267,969, dated November 21, 1882; and it has for its object to simplify and cheapen the construction shown in said patent, and to render the device lighter and stronger and more durable and more efficient in operation.

The novelty in the present instance resides in the peculiarities of construction and the new combinations of parts, all as more fully hereinafter described, shown in the drawings, 30 and then particularly pointed out in the claim.

The invention is clearly illustrated in the accompanying drawings, which, with the letters of reference marked thereon, form a part of this specification, and in which—

35 Figure 1 is a longitudinal vertical section of a washing-machine constructed in accordance with my invention. Fig. 2 is a vertical cross-section of the same. Fig. 3 is a side elevation of the cylinder, and Fig. 4 is a detail 40 perspective view of one of the cylinder-supporting castings.

I dispense with the cast-iron sudsing-frame of the patent, and in its place use a wire one, which I have found to be much lighter and 45 stronger, and which does not tear out the sides of the machine. I make the cam integral with the journal-bearing casting, and otherwise improve upon the prior construction, as will more fully hereinafter appear.

50 Referring now to the drawings by letter, A designates a vessel or tank, in which the wa-

ter is placed to be heated, it having a cover, B, adapted to be removed when desired. In the center of the vessel or tank A, and upon diametrically-opposite sides thereof, are the 55 castings C, having vertical arms *a* extending up the sides of the vessel and terminating at their upper ends in bearings *b*, for the journals of the clothes-cylinder to take the strain off the vessel, the said journal-bearings extending outside the boiler any desired distance. Cast integral with the casting C is the cam D, the back side portions, *c*, uniting the casting with the cam, being designed to have a flat bearing against the side of the vessel, 65 as shown, the said casting being preferably provided with a series of holes, *d*, for the reception of rivets or other suitable means for securing it to the sides of the vessel.

The clothes-cylinder E is placed between 70 two castings, F, having radial arms *e*, two of which (or, if preferred, all of them) extend way across the face of the cylinder, and those two extending across the upper or smaller section, G, of said cylinder are pivoted on the hubs of 75 the castings F, as shown at *f*, and are designed to hold said section G in place, and yet can be readily turned down till they come below the upper edge of the lower section, E, to disengage said section, as shown by dotted lines 80 at the left of Fig. 3, when it is desired to remove the said upper section for the purpose of taking out or putting in the clothes. Catches *g*, of flat spring metal, secured at one end to the lower portion, are provided to hold the 85 arms in the position shown by dotted lines at the left of Fig. 3.

The centers of the castings F are provided with sockets *h*, in which fit the journals *i* of the clothes-cylinder E.

Upon the interior faces of the larger portion of the clothes-cylinder E are placed the sudsing-frames H, each consisting of a light wire frame, I, hinged to the inner face of the said portion by means of suitable connections, 95 as shown at *j*, and provided at their lower ends with the arms *k*, which pass through a slot in the cylinder, as shown, and engage the cams D. The frames I are covered with open wire-work *l*, of sufficient mesh to allow the water to readily pass therethrough, and yet not allow the escape of the clothes. The frames I

are formed with suitable recesses or bends, *m*, for the reception of the fingers to handle the sudser when necessary.

The operation is apparent. When the cylinder *E* is rotated, the arms *k* operate against the cams to draw the sudsing-frame toward the center, and thereby compress the clothes in the cylinder, the elasticity of the clothes forcing the sudsing-frame back when the arms *k* have ceased to act upon the cams. At each revolution of the cylinder the clothes change their places and are constantly acted on by the forcing out of the dirty suds, and again receiving a fresh supply of water through the ports *n*, formed by a V-shaped plate being set in between the walls of the cylinder below openings upon its periphery, and the clothes being acted upon by the compressing and releasing of the sudsing-frame, operated by the

arms *k* and cams, the dirty water is forced out with greater effect than it could be done by the weight of the clothes alone.

What I claim as new is—

In a washing-machine, the combination, with the cylinder having removable portion *G*, of the castings *F* and the radial arms pivoted to said castings and extended across the face or periphery of said removable portions, and the catches *g* on the lower portion, substantially as and for the purpose specified.

In testimony that I claim the above I have hereunto subscribed my name in the presence of two witnesses.

HENRY SEAMAN.
